F. ORDAKOWSKY

MECHANICALLY OPERATED FAN

Filed July 18, 1921

Patented Oct. 27, 1925.

1,558,912

UNITED STATES PATENT OFFICE.

FELIX ORDAKOWSKY, OF CLARKSBURG, WEST VIRGINIA.

MECHANICALLY-OPERATED FAN.

Application filed July 18, 1921. Serial No. 485,453.

To all whom it may concern:

Be it known that I, FELIX ORDAKOWSKY, a citizen of the United States, residing in Clarksburg, in the county of Harrison and 5 State of West Virginia, have invented certain new and useful Improvements in Mechanically-Operated Fans, of which the following is a full and complete specification, reference being had to the accompanying 10 drawing.

The present invention has reference to a portable ventilating fan and the main object is to provide a structure of this character simple and rugged in construction and 15 cheap to manufacture.

It is a further object of the present invention to provide a portable mechanically driven ventilating fan of adaptable construction so that the fan may be either 20 placed on a table or pedestal or suspended from over head. In order to render the invention entirely clear a preferred embodiment is illustrated in the accompanying drawings in which Fig. 1 shows a view of 25 the complete structure;

Fig. 2 shows a cross section of the same, and

Fig. 3 shows a suspending means adapted to be used with the structure when the same 30 is used as an over-head fan.

In the form illustrated the fan comprises a box or enclosure 1 constructed of wood or metal, in which the clock work for operating the fan is enclosed. Mounted upon the top 35 of this enclosure and fitted over or journaled upon a rotating shaft hereinafter described is a pedestal 2 having an enlarged top 3 in which a pair of bevel gears 4 and 5 are located. By means of these gears motion is transferred from the vertical shaft 6 to the horizontal shaft 7 upon which the fan 40 blades 8 are mounted. If desired, a suitable fan guard may be provided for the fan blades the same being mounted upon the enlarged head 3, but as the fan guard forms no part of the present invention the same is 45 not shown.

The power for operating the fan through 50 the medium of shaft 6 is obtained from a powerful spiral spring 9. This spring is wound by means of a crank 10 removably fitted on a winding shaft 11 carrying at its inner end a spur gear 12 meshed with a gear 13 which is rigidly fixed to the inner end of 55 the spring. A coil spring 14 closely encircles

the winding shaft 11, the inner end of this coil spring 15 being fixed to the frame of the driving mechanism and the outer end being free. When the winding shaft 11 is rotated by the crank in a clock-wise direction the spring 14 tends to loosen and permit shaft 11 to freely rotate and the spring 9 can therefore readily be wound. When winding effort is no longer applied to the winding shaft 11, the spring 9 will, of course, tend to rotate shaft 11 in an opposite or counter clock-wise direction. Such rotation, however, serves to tighten spring member 14 about shaft 11 so that the same is securely gripped and prevented from rotation. The spring member 14, therefore, serves as 60 a noiseless and efficient ratchet and pawl mechanism.

Gear wheel 16 is carried by the spring drum and serves to drive the small pinion 75 17, which is fixed to gear 18, the gear 18 in turn meshes with pinion 19 mounted on shaft 20 at the upper end of which is carried gears 21 and 22. Gear 21 meshes with pinion 23 mounted upon the lower end of 80 fan operating shaft 6. By means of the large gear reduction existent between the spring drum 9 and the shaft 6 and the further reduction due to bevel gears 4 and 5, the fan 8 will operate for several hours upon 85 one winding of the spring.

Pinion 22 operates shaft 24 through the medium of a gear 25 and pinion 26. A disc 25^a is carried at the upper end of shaft 90 24 and has a plurality of holes 26 located at various distances from its center. A lug 27 is fixed to the pedestal 2 and has pivotally mounted thereon a connecting rod 28. The outer end of this connecting rod carries a pin 29 which may be inserted in any of the holes 26 or in the stationary hole 30 in the top frame of the enclosing member 1. When the pin 29 is inserted in any of the holes 26, the pedestal is given an oscillating movement, the extent of which depends upon the particular hole in the disc 25^a which is selected. When the pin 29 is inserted in the stationary hole 30, the fan 95 no longer oscillates but is of the fixed or stationary type.

A gear 31 is fixed to the lower end of shaft 20 and operates to drive a centrifugal governor 32 through the medium of the gear 33. The governor weights function to lift a flat disc 34 against a felt 35 carried 100 105 110

in the short end of the bell crank lever 36. The position of felt 35 with respect to the governor disc 34 and therefore the speed of the fan is regulated by means of 5 a rod 37 carrying at its outer extremity a milled head 38. By turning this milled head the rod may be screwed to a greater or less extent into post 39 against the longer end of the bell crank lever 36, which is 10 resiliently urged against the inner end of rod 37 by means of a leaf spring 40.

When it is desired to convert the fan from the ordinary type into the ceiling type, the pedestal 2 with the fan and associated 15 gearing 4 and 5 is removed and a shaft 41 is inserted through the top of the enclosing receptacle. This shaft is also inserted through a gear 42 meshing with an idler gear 43 carried on a shaft 44 and transmitting motion from the gear 21 to the shaft 41. A fan of the ceiling type is mounted upon the lower end of shaft 41 and the entire structure is suspended by means of 20 hanger illustrated in Fig. 3, which has a plurality of screw holes 45 adapted to cooperate with screw holes 46 of the enclosing receptacle 1.

The winding crank 10 is removable and 25 may be enclosed within a recess provided with the receptacle 1. A cover for the top of receptacle 1 may also be provided for

enclosing the oscillating structure and having a single opening for the pedestal 2 to project through.

It is obvious that details of construction 35 and arrangement of parts may be varied without departing from the spirit of the invention as set forth in the appended claims.

What I claim is:

1. In a mechanical fan, in combination 40 with a base including a spring motor and a vertical rotating shaft driven thereby, of a pedestal journalled on said shaft, a cam driven from said spring motor, a link connecting said pedestal and cam, a fan shaft 45 journalled in said pedestal and gearing between the said shafts.

2. In a mechanical fan, the combination 50 with a base including a spring motor and a vertical rotating drive shaft actuated thereby, a pedestal journalled on said shaft, a fan shaft carried by said pedestal and operated by said vertical shaft, a cam rotated by said spring motor in a plane perpendicular to said pedestal, a link pivoted to said pedestal and adapted selectively for engagement with said cam and for anchoring attachment to said base. 55

In testimony whereof, I hereunto affix my signature.

FELIX ORDAKOWSKY.
